UNITED STATES PATENT OFFICE.

GUSTAVE E. VILLARET, OF LEONIA, NEW JERSEY, ASSIGNOR TO WILLIAM R. NOE & SONS, OF NEW YORK, N. Y., A COPARTNERSHIP.

DESIGN FOR A BASE FOR PORTABLE ELECTRIC LAMPS.

Application filed May 21, 1925. Serial No. 13,520. Term of patent 7 years.

To all whom it may concern:

Be it known that I, GUSTAVE E. VILLARET, a citizen of the United States, residing at Leonia, in the county of Bergen and State of New Jersey, have invented a new, original, and ornamental Design for Base for Portable Electric Lamps, of which the following is a specification, reference being had to the accompanying drawing, forming part thereof.

Fig. 1 is a side elevation showing my new design.

Fig. 2 is a side elevation, the base portion being omitted.

Fig. 3 is a plan view of the base taken on the line 3—3 in the direction indicated by the arrows, the upper portion being omitted for the sake of clearness.

I claim:

The ornamental design for a base for portable electric lamps, as shown.
